Primary Examiner — Darcey E Gottschalk*Assistant Examiner* — Vanessa M. Pursley(74) *Attorney, Agent, or Firm* — Polsinelli, P.C.(57) **CLAIM**

The ornamental design for a food tray, as shown and described.

DESCRIPTION

FIG. 1 is a perspective view of a food tray showing our new design;

FIG. 2 is a top view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a bottom plan view thereof.

In FIG. 7, the evenly-spaced broken lines represent portions of a food tray that form no part of the claim.

The food tray is shown with a symbolic break in its height via dash-dot-dot-dash lines. The appearance of any portion of the article between the dash-dot-dot-dash lines forms no part of the claimed design.
